DOOR HANDLE ASSEMBLY

Emory Glenn Simpson, Detroit, Mich., assignor to
Ternstedt Manufacturing Company, Detroit,
Mich., a corporation of Michigan

Application July 5, 1938, Serial No. 217,447

3 Claims. (Cl. 292—167)

In an automobile the remote inside door handle is usually located where it is readily accessible for operation by a youngster. Many accidents have occurred by youngsters operating the remote inside door handle to unlatch and open the vehicle door while the vehicle was in motion. Other accidents have occurred by occupants of the car unintentionally striking or actuating the remote inside door handle to retract the bolt and throw the door open while the vehicle was in motion.

It is the object of this invention to obviate the above-mentioned danger inherent in the present day automobile inside door handle. This object has been achieved by an inside door handle which can be latched in its normal position, that is, the position it occupies when the door latch bolt is projected.

It is also an object of this invention to produce a remote inside door handle which, upon being released after retracting the bolt, upon returning to normal position automatically locks itself in this position.

This invention also contemplates an inside door handle provided with a latch for latching it in normal position, which latch at the option of the operator can be rendered either effective or ineffective to latch the inside door handle.

In the drawings:

Fig. 1 is a fragmentary inside elevation of an automobile door showing the inside door handle and detent therefor.

Fig. 2 is an enlarged perspective view of the inside door handle and detent therefor with the handle in latched position.

Fig. 3 is a perspective view of the handle with the detent inoperative.

Fig. 4 is a detail showing the mounting of the handle on the door.

Fig. 5 is a section along the line 5—5 of Fig. 2.

Fig. 6 is a section along the line 6—6 of Fig. 3.

Fig. 7 is a detail of the detent for the inside door handle showing the detent effective to latch the inside door handle.

Fig. 8 is a detail of the detent showing the detent ineffective to latch the inside door handle.

Fig. 9 is a front elevational detail view of the detent showing its position when effective to latch the door handle.

Fig. 10 is a front elevational view of the detent corresponding to Fig. 8 with the detent ineffective to latch the inside door handle.

Fig. 11 is an exploded view of the detent.

Fig. 12 is a perspective showing a modified form of detent.

Fig. 13 is a section along the line 13—13 of Fig. 12 showing the handle blocked.

Fig. 14 is a section similar to Fig. 13 showing the inside handle passing over the detent.

Referring more particularly to the drawings there is shown an automobile door 1 provided with a latch comprising a spring projected latch bolt 2 and an inside door handle 3 which is connected to the bolt 2 by a draft link 4. The bolt 2 can be retracted by turning the handle 3 counterclockwise as viewed in Fig. 1.

The inside door handle 3 takes the form of a lever which is fixed on a spindle 5 which is journaled in the bearing support plate 6 (which is fixed to the lock board 1) and in the bearing plate 8 which is fixed to the plate 6. A lever 9 is also fixed on the spindle 5 to turn therewith. The lever 9 is connected to the draft link 4. The torsion spring 10 is mounted upon the spindle 5. One end of the spring is secured to the plate 6 as at 11 and the other end engages behind the lug 12 on the lever 9. Thus each time the handle 3 is turned down (Fig. 1) the lever 9 turns clockwise (Fig. 4) and, acting through draft link 4, retracts the bolt. This winds up torsion spring 10. When the handle 3 is released, the torsion spring returns the handle to its normal position, Fig. 1. When the latch bolt 2 is projected by its spring in the usual manner, the bolt acts through draft link 4 and lever 9 to return the handle 3 to normal position.

It is proposed to lock the handle 3 in its normal position so that it cannot be turned to retract the bolt preliminary to opening the door. To this end a handle blocking device in the form of a detent is used. This detent comprises a plunger 14 slidably mounted in the housing 15 and backed up by a coil spring 16. The plunger 14 is provided with a shoulder 17 which, when the plunger is projected, engages beneath the lever handle 3 to block it and prevent turning of the same to retract the bolt. The plunger 14 is retained within the housing 15 by a pin 18, one end of which slidably engages the housing in the T slot 19 and the other end of which fits in the recess 20 in the detent 14. The pin 18 is provided with a shoulder 21 and is backed up by a coil spring 22 which yieldably projects the pin 18 into the T slot 19.

As shown in Figs. 1, 2 and 5, the plunger detent 14 is projected and the handle 3 is locked in its normal position with the latch bolt 2 projected. To withdraw the latch bolt it is first necessary to press the plunger detent 14 inwardly against the coil spring 16 so that the

shoulder 17 clears the handle 3. At this time the handle 3 can be turned counterclockwise, Fig. 1, to retract the bolt 2.

When the handle 3 is released, either or both the bolt spring or the spring 10 swings the handle clockwise, Fig. 1, to its normal position. As the handle swings back to its normal position it automatically retracts and passes by the plunger detent 14. To this end the underface 23 of the shoulder portion 17 of the plunger detent 14 takes the form of a portion of a sphere, that is, the face 23 is rounded so that the handle 3 can readily cam back or retract the detent 14 as it swings back to normal position. As soon as the handle passes the shoulder 17, the spring 16 again projects the plunger detent 14 to lock the handle in its normal position.

The plunger detent 14 optionally can be rendered ineffective to block the handle 3. To accomplish this purpose the plunger detent 14 is pressed inwardly of the housing 15 to fully retracted position, Fig. 6. This compresses spring 10. After being fully retracted within the housing 15 the detent 14 is then turned either clockwise or counterclockwise a few degrees, as indicated in Figs. 3, 8 and 10. At this time the pin 18 passes out of the stem portion of the T slot 19 into one or the other of the notches 25 in the T slot 19. The pin 18 is yieldably held in one or the other of the notches 25 by the spring 16. When the detent 14 is thus held in retracted position, the handle 3 can be freely turned on its spindle and the detent is ineffective to block the turning of the handle.

To release the detent 14 from its ineffective position, Figs. 3 and 6, it is only necessary to turn it back to the position indicated in Fig. 9 which disengages the pin 18 from the notch 25 in the housing 15 and aligns the pin with the stem portion of the T slot 19 whereupon the spring 16 again projects the detent to its effective position.

In the modified form of the invention shown in Figs. 12 through 14, the handle 3 is blocked by a swinging detent 38 pivotally mounted on the stamped casing 31 by pin 32. The casing 31 is secured by screws 33 to the lock board 34. The detent 38 is normally held in projected position by the spring 35 which is mounted on the pin 32.

In this form of the invention the detent can be applied to the face of the door without necessitating any cutting out of the inside door panel and lock board. As indicated in Figs. 12 and 13, the handle cannot be turned down to retract the latch bolt because it is blocked by the detent 38. The detent 38 must first be retracted into the casing 31 before the handle 3 can be turned. When the handle 3 is turned to retract the latch bolt and then released, it returns to its normal position and is automatically dogged by the detent 38. As shown in Fig. 14, as the handle returns to normal position it cams the detent 38 to retracted position and after the handle passes

over the detent, the spring 35 projects the detent under the handle 3 to block the same.

I claim:

- 5 1. In combination with a movable automobile door handle, a plunger member, a spring for projecting the same into the path of movement of the handle to block movement of the same, a housing member in which the plunger member is reciprocable and rotatable, a pin carried by one of said members and a T slot in the other of said members, the said pin engaging the stem portion of the T slot in the retraction and projection of the plunger member and the said pin interengaging one or the other of the cross portions of the said slot upon retraction of the plunger member and turning of the same in either direction to retain the plunger member retracted.
- 10 2. In combination with a swinging automobile inside door handle, a detent projectable into the path of movement of the handle to block movement of the handle and retractable out of the path of movement of the said handle, said detent comprising a projectable and retractable plunger member, a housing member for the same, a pin carried by one of the said members and a slot in which the said pin travels carried by the one of said members, said slot having a portion extending generally in the direction of reciprocation of the plunger and other portions extending transversely thereof in substantially opposite directions whereby when the detent plunger is retracted the same can be turned in either direction in its housing to interengage said transversely extending slot portions to lock the detent in retracted position, the said pin and first mentioned portion of the slot cooperating to prevent rotation of the plunger in the housing and the transversely extending portions of the slot permitting a limited rotation of the plunger in the housing when the pin reaches such transverse portions of the slot.
- 15 3. In combination with a movable automobile door handle, a cylindrical plunger member, a spring for projecting the same into the path of movement of the handle to block movement of the same, a housing member in which the plunger member is reciprocable and rotatable, a pin carried by one of the members and a slot in the other of said members having a longitudinal portion and a lateral portion, the said pin engaging the longitudinal portion of the slot in the retraction and projection of the plunger member and the said pin interengaging the lateral portion of the said slot upon retraction of the plunger member and turning of the same to retain the plunger member retracted, said plunger member being provided at its outer end with a cut away portion having a flat face whereby the outer end of the plunger member may be conveniently grasped by an operator when the plunger member is turned to latch the same in its retracted position.

EMORY GLENN SIMPSON.
